UNITED STATES PATENT OFFICE.

EUGENE IRVING HANSON, OF NEW ROCHELLE, NEW YORK, ASSIGNOR TO H. R. MALLINSON & CO., A FIRM COMPOSED OF HIRAM ROYAL MALLINSON AND EUGENE IRVING HANSON, OF NEW YORK, N. Y.

DESIGN FOR A COLOR-DISPLAY CARD.

52,651.

Specification for Design.

Patented Nov. 12, 1918.

Application filed July 18, 1917. Serial No. 181,454. Term of patent 3½ years.

To all whom it may concern:

Be it known that I, EUGENE IRVING HANSON, a citizen of the United States, and a resident of New Rochelle, county of Westchester, and State of New York, have invented a new, original, and ornamental Design for a Color-Display Card, of which the following is a specification, reference being had to the accompanying drawings, showing in Figure 1 a face view of a color-display card bearing and incorporating my design and in Fig. 2 a fractional section thereof along the line 2—2 of Fig. 1.

In the drawing "a" designates the card upon which is produced a golf course with golf players, "b" designates apertures in said card representing hole indicators in the golf course, and "c" designates fabric visible through said apertures "b." The shading in

the drawing represents color, it being understood, however, that my design is not limited to the specific colors indicated by the shading, the shading being used merely for the purpose of showing that pieces of fabric of different colors are visible through the different apertures, and that each golf player is represented as wearing a gown in the manufacture of which a fabric is used of the color identical with the color visible through the adjoining aperture in the color display card.

It is to be understood that my claim includes all substantial equivalents of my design as shown and described.

I claim:

The design for a color display card substantially as shown and described.

EUGENE IRVING HANSON.
